(57) CLAIM

The ornamental design for a "M" style guard, as shown and described.

DESCRIPTION

FIG. 1 is a perspective view of a "M" style guard showing my new design, the broken lines are for illustrative purposes only and form no part of the claimed design;

FIG. 2 is a front elevation view thereof;

FIG. 3 is a front view of the guard taken from FIG. 1;

FIG. 4 is a left side view of the guard taken from FIG. 1;

FIG. 5 is a right side view of the guard taken from FIG. 1; and,

FIG. 6 is a top plan view of the guard taken from FIG. 1.
